UNITED STATES PATENT OFFICE.

JOHN H. LEHMANN, OF WAVERLY, MARYLAND.

BROODER.

1,129,806.

Specification of Letters Patent. Patented Feb. 23, 1915.

Application filed May 22, 1914. Serial No. 840,303.

To all whom it may concern:

Be it known that I, JOHN H. LEHMANN, a citizen of the United States, residing at Waverly, in the county of Baltimore and State 5 of Maryland, have invented new and useful Improvements in Brooders, of which the following is a specification.

This invention relates to brooders, and it has for its object to produce a device of this 10 class which will be simple in construction and which may be readily adjusted and manipulated to suit the condition of the chicks as they acquire their growth.

With these and other ends in view which 15 will readily appear as the nature of the invention is better understood, the same consists in the improved construction and novel arrangement and combination of parts which will be hereinafter fully described 20 and particularly pointed out in the claims.

In the accompanying drawing has been illustrated a simple and preferred form of the invention, it being, however, understood that no limitation is necessarily made to the 25 precise structural details therein exhibited, but that changes, alterations and modifications within the scope of the claims may be resorted to when desired.

In the drawing,—Figure 1 is a perspective view of the improved brooder with the lid 30 open and with the interior fixtures removed. Fig. 2 is a perspective detail view of the interior supporting frame with the draft shield connected therewith at one end. Fig. 35 3 is a perspective view of one of the curtains. Fig. 4 is a vertical sectional view of the 40 brooder with the interior fixtures in position and looking toward the front. Fig. 5 is a sectional detail view taken on the line 5—5 in Fig. 4, with a portion of the draft shield removed.

Corresponding parts in the several figures are denoted by like characters of reference.

The brooder consists of a wooden box 15 45 which is raised from the ground by means of legs or supports 16, the parts of the structure being assembled by means of screws 17 in order that said parts may be readily knocked down or taken apart for convenience in shipment and storage. The box 15 has a lid 18 which is connected with the rear wall thereof by means of hinges 19. The lid has a large vent opening 20 which is covered 50 with wire mesh fabric 21 and in which a lid or plug 22 may be seated when desired in

cold or damp weather. A smaller vent opening 23 is provided in a side wall of the box. The front wall of the latter has a doorway 24 for the chicks. Each side wall of the box is provided on its inner face with a horizontal cleat 25, said cleats serving to support a frame 26, the front and rear members of which are provided with alining grooves 27 to support rods 28 having curtains 29 of flexible, preferably textile material, said curtains being provided with slits 30 to permit the chicks to pass readily. The lid 18 is provided on its underside with transverse parallel cleats 31 located, respectively, near the front and rear edges of said lid. When the 70 parts are assembled, that is to say, when the frame 26 is in position and the curtain rods or supports 28 have been positioned on said frame, the closing down of the lid will cause the cleats 31 to abut on the curtain supporting rods, thereby retaining said rods in position against accidental displacement by the moving about of the chicks within the brooder. At the same time, air will be permitted to circulate freely above the curtain 75 support, rods 28 and beneath the lid 18, thus causing all the interspaces between the curtains 29 to be freely and fully ventilated.

For the further protection of the chicks in cold and damp weather, I provide a draft 80 shield consisting of a square 32 of flexible material, such as that of which the curtains 29 are made. Said shield is provided at each end with a rod 33 having projecting ends adapted to engage keepers 34 at the corners 85 of the frame 26. This shield when stretched in position, as indicated in Figs. 4 and 5, will protect the interspaces between the curtains 29 from drafts. A curtain 35 having a rod 36 may be suspended adjacent to the 90 opening 24, as indicated in Fig. 4, keepers 37 being provided for the accommodation of the ends of the rod.

In the use of this brooder, as the chicks attain their growth, some of the curtains 29 100 may be removed, thus adapting the brooder to the growing condition of the chicks and avoiding hampering their ability to move freely about within the brooder, which would result in checking their development.

Having thus described the invention, what is claimed as new, is:—

1. In a brooder, a box having a doorway in the front thereof, said box including side walls having horizontal cleats on the inner 110

faces thereof, a lid hingedly connected with the rear wall of the box and having a vent opening, said lid being provided with cleats on its under face adjacent to its front and rear edges, a frame supported on the cleats of the side walls, said frame having alining grooves in the front and rear side members thereof, and curtain supporting rods supported in said grooves and contacted with 10 by the cleats on the underside of the lid when the latter is closed.

2. In a brooder, a box having a front doorway, a lid hingedly connected with the box and having a vent opening, a plurality of 15 curtain supporting rods mounted detachably within the box and spaced below the lid, and means associated with the lid for maintain-

ing said rods in adjusted position when the lid is closed.

3. In a brooder, a box having a front doorway, a lid connected with the box and having a vent opening, a frame supported detachably in the box and having keepers at the corners thereof, a plurality of curtain supporting rods supported on the frame, and a flexible draft shield stretched on the frame and having rods engaging the keepers. 20 25

In testimony whereof I affix my signature in presence of two witnesses.

JOHN H. LEHMANN.
